CLAIM

The ornamental design for a flexible display screen with
graphical user interface, as shown and described.

DESCRIPTION

FIG. 1 is a front view of a first embodiment of my new
design for a flexible display screen with graphical user
interface.

FIG. 2 is a front view thereof shown in a bending position.
FIG. 3 is a back view thereof shown in a bending position.
FIG. 4 is a bottom view thereof shown in a bending position.
FIG. 5 is a perspective view thereof shown in a bending
position.

FIG. 6 is a front view of a second embodiment of my new
design for a flexible display screen with graphical user
interface.

FIG. 7 is a front view thereof shown in a bending position.
FIG. 8 is a back view thereof shown in a bending position.
FIG. 9 is a bottom view thereof shown in a bending position;
and,

FIG. 10 is a perspective view thereof shown in a bending
position.

The broken lines illustrating an electronic device illustrate
portions of the article, and form no part of the claimed
design. The broken line showing the flexible display screen
and portions of the graphical user interface are included for
the purpose of illustrating portions of the article and form no
part of the claimed design.

1 Claim, 10 Drawing Sheets
